UNITED STATES PATENT OFFICE

2,328,049

SHOE CONSTRUCTION

Arthur E. Bowman, St. Louis, Mo.

Application April 29, 1942, Serial No. 440,945

2 Claims. (Cl. 36—13)

The present invention relates generally to shoes and more particularly to that type of shoe wherein the leather sole construction is replaced by one of a generally less resilient material.

An object of the present invention is to provide a novel shoe construction incorporating a substantially non-resilient sole construction.

Another object is to provide a novel shoe in which the upper is of soft material, as leather, and the sole construction is of a substantially non-resilient non-flexible material, such as wood.

Another object is to provide a novel shoe construction involving a breaking substantially non-resilient sole construction.

Another object is to provide a practical shoe construction adapted to replace the conventional shoes now widely used.

Another object is to provide a shoe constructed without metal parts or elements.

Another object is to provide a novel wooden-soled shoe of practical construction.

Other objects are to provide a novel shoe construction which is inexpensive to make, which may be easily and readily manufactured, which is comfortable, which may be readily repaired, and which is designed and adapted to relieve the pressure in the shoe industry in regard to leather necessary in the conventional construction of present day leather shoes.

Other objects and advantages are apparent from the following description taken in conjunction with the accompanying drawing in which:

Fig. 1 is a plan view of a wooden shoe sole constructed in accordance with the teachings of the present invention;

Fig. 2 is a side view of the sole shown in Fig. 1;

Fig. 3 is a section on the line 3—3 of Fig. 2;

Fig. 4 is side view of a leather upper constructed to cooperate with the sole shown in Fig. 1;

Fig. 5 is a section on the line 5—5 of Fig. 4;

Fig. 6 is a perspective view of a wooden pin employed in holding the upper of Fig. 4 in cooperative relationship with the sole of Fig. 1;

Fig. 7 is a side view of a completed shoe incorporating the present invention;

Fig. 8 is a section on the line 8—8 of Fig. 7;

Fig. 9 is a plan view of a modified sole construction; and

Fig. 10 is a section on the line 10—10 of Fig. 9.

Referring to the drawing more particularly by reference numerals, 15 (Fig. 7) indicates generally a shoe constructed in accordance with the 55

concepts of the present invention which includes an upper construction 16, a sole construction 17, and a heel 18.

The upper construction 16 shown includes a toe and vamp 20 and rear quarter 21. Suitable string apertures 22 are provided. A strip 23 (Fig. 8) of leather, or the like, is secured to the lower inner face of the upper construction 16 by stitching 24. The strip 23 extends around the full perimeter of the upper construction 16 and assists in maintaining it in the configuration shown in Fig. 4.

The sole construction 17 is of wood and of the configuration shown in Figs. 1 and 2. A continuous groove 26 (Figs. 1 and 3) is formed in the upper face of the sole construction 17 adjacent the edge thereof. Spaced apertures 28 extend inwardly from the sides of the sole construction 17 and are of a depth and disposition 20 passing through the groove 26.

The upper construction 16 fits onto the sole construction 17 with the full lower edge thereof and the attached strip 23 extending into the groove 26 (Fig. 8). A wooden pin 29, slightly larger than the apertures 28 in diameter and length, is driven into each aperture 28 and through the upper construction 16 and the attached strip 23. The pins 29 are employed in sufficient number to securely fasten the upper construction 16 to the sole construction 17.

The heel 18 is secured to the sole construction 17 by suitable cement. Dowel pins (not shown), or the like, may be employed.

In Figs. 9 and 10 there is shown a modified sole construction 31. A resilient segment 32 of rubber, or other material, connects a forward portion 33 and a rear portion 34 of the sole construction 31. Registering and abutting surfaces of the portions 33 and 34 and the segment 32 are 40 secured by suitable cement.

In use, the shoe 15 is non-flexible, but is comfortable in view of the soft upper construction 16 and the configuration of the sole construction 17. A rocking action affording sufficient compensation for flexibility is provided. In the modification shown in Figs. 9 and 10, flexibility is achieved through the resilient segment 32. This type of shoe may be more preferable for some wearers.

It is to be observed that the present shoe 15 is of simple sturdy construction. The wooden sole construction 17 manifestly will wear for a long time and can be repaired either by cementing or otherwise affixing repair wedges to the heel or toe. Total replacement of the sole construc-

tion 17 is easily accomplished. It is clear from Fig. 10 that the resilient segment 32 is subjected to only slight wear due to positioning and will, therefore, last indefinitely.

It is manifest that the configurations of the upper construction 16 and sole construction 17 may be altered. Furthermore, the sole construction 17 and the pins 29 may be of other materials than wood, although, a light wood such as bass wood has been found to be an excellent material. The embodiment of the present shoe disclosed and described are entirely without metal.

It is apparent from the foregoing description and the accompanying drawing that the present invention fulfills all of the objects and advantages sought therefor.

It is to be understood that the foregoing description and the accompanying drawing are given by way of illustration and example and not for purposes of limitation, the present invention being limited only by the claims which follow.

I claim:

1. In a shoe construction, a sole having an upper receiving groove therein, an upper having an edge portion adapted to be inserted into said groove, a separate strip attached to the upper adjacent said edge portion, said strip extending adjacent the edge, and the strip and edge being adapted to be inserted into said groove, and means to secure the edge of the upper and the strip in the groove.
- 5 2. In a shoe construction, a sole having an upper receiving groove adjacent the edge thereof, an upper having an edge portion therearound for insertion into said groove, a separate strip, means securing the strip around the edge portion to reinforce the same where it is to be inserted into the groove, said strip and the edge together being adapted to be inserted into the groove, and means for securing the said upper edge and strip in the groove.

ARTHUR E. BOWMAN.
